UNITED STATES PATENT OFFICE

150,804

DESIGN FOR A CLOCK

Adolph J. Nelson, Oak Park, Ill., assignor to
Boyco, Inc., Chicago, Ill., a corporation of
Illinois

Application April 14, 1948, Serial No. 145,718

Term of patent 7 years

(Cl. D42—7)

To all whom it may concern:

Be it known that I, Adolph J. Nelson, a citizen of the United States of America and a resident of Oak Park, in the county of Cook and State of Illinois, have invented a new, original, and ornamental Design for a Clock, of which the following is a specification, reference being had to the accompanying drawing, forming a part thereof, and in which:

Fig. 1 is a front elevational view of a clock, showing my new design;

Fig. 2 is a side elevational view of the same; and

Fig. 3 is a top plan view of the same.

I claim:

The ornamental design for a clock, as shown.

ADOLPH J. NELSON.
